UNITED STATES PATENT OFFICE.

ROBERT HOLZ, OF CINCINNATI, OHIO, ASSIGNOR TO THE RICHARDSON COMPANY, OF LOCKLAND, OHIO, A CORPORATION OF OHIO.

STRIPPING AND FILLING PRESS.

Application filed April 30, 1923. Serial No. 635,550.

My invention relates to presses which are employed for forming various articles between male and female dies, and in which a stripping action is had, during which the molds may be filled, and subsequently a preliminary pressing action.

In the production of battery boxes from a plastic material, I have evolved a process whereby the male and female parts are separable from the presses operating upon them, to the end that a cycle can be followed, of first filling the female mold, then inserting and lining up the male dies, then transporting the assembled parts to another press for imparting high pressure, and finally passing the assembled mold parts around through any other steps of treatment desired to the first press again, where the male parts are lifted and stripped away from the female parts.

In this application I wish to cover the filling and stripping press, by itself and in combination with a detachable mold.

Among other things, it is my object to provide in the press for a horizontally engaging and disengaging connection between the press and the mold parts. It is also my object to provide a simple stripping mechanism, whereby the male part is stripped away from the article molded, and is lifted out of the female part or pushed out of it, or both, thereby insuring a perfect stripping of the article, without tearing it or distorting its shape.

The above objects I accomplish by that certain construction and arrangement of parts to be hereinafter more specifically pointed out and claimed.

In the drawings:

Figure 1 is a central vertical section taken through the device. Figure 2 is a front elevation of the device.

Referring to the press parts, I show a base 1, standards 2, 2, thereon, and a cylinder 3, in which is a hydraulic ram 4. This ram controls the reciprocation of a plunger shaft 5. On the lower end of the cylinder surrounding the bushing 6, that defines the journals for the shaft 5, is a depending housing 7, which terminates in an orifice 8, considerably larger than the shaft. The edges surrounding this opening act as an abutment in the stripping action of the press.

In the bed of the press is mounted a hy-

draulic ram 9, reciprocating in a cylinder 10, and carrying a plunger shaft 11, which rises up into the female mold part through the hole 11^a in the bed to act as an ejector.

I have not shown the connection and valves for a pressure medium in my press, as these details form no part of my invention.

On the bed of the press are a pair of plates or some other convenient form of device providing a dovetail overhanging member 12 on each side of the top of the bed.

The lower end of the plunger shaft 5 is equipped with a head 13, formed with a T-shaped downward projection 14, that is intended to engage the male die parts detachably while the members 12 engage the female part.

As a die I have shown in Figure 2 a section of a female die part, 18^a, a male die part having a head 14^a, and a plunger or plungers 15, and a stripper plate 16, having depending webs 17 that enter the female mold and surround the upper portions of the plungers 15 when they are in the mold.

On the corners of the stripper plate, are located vertical posts 18, the head of the male die being provided with holes to slidably engage over said posts. The posts have heads to prevent the male die from coming clear away from the stripper plate.

The head of the male die engages the stripper plate by contact therewith of its overhanging portions 19, and a T-shaped groove is formed in the upper portion of this male die head, which fits the T-shaped projection on the press shaft 5.

The posts 18 on the stripper plate are set so as to contact when drawn upwardly with the housing that surrounds the shaft 5, where it emerges from the upper press cylinder.

As so constructed the press is adapted to receive the mold or die parts, by sliding of the flange 20 on the female part beneath the overhanging members 12 on the press bed, and by lowering the shaft 5, so that at the same time the male die head will slide horizontally over the T-shaped end of said shaft 5.

The lifting of the shaft 5 will then cause the male die to rise, and if the article being pressed has been closely engaged between the plungers of the male die, the article will

rise with the male die, and the stripper plate will remain in its lowermost position, as shown in Figure 1. If the article does not come out with the male die plungers, then the lower shaft 11 is raised. The female die is formed with a bottom section 21, which can be pushed upwardly through the said die, and this section is centered over the shaft 11, when the die is in position with the press shaft 5 in full engagement with the head of the male die. This action will force the article out, together with the male die and the stripper plate.

When the shaft 5 has been withdrawn upwardly through part of its path, the ends of the posts on the stripper plate strike the web or housing 7, which results in a withdrawal of the plungers of the male part upwardly through the stripper plate webs, until the shaft 5 has reached the upward limit of its movement, which will be co-incidental with the male die head reaching the heads on the ends of the stripper shaft posts.

The article adhering to the plungers of the male die will then be entirely stripped away therefrom, and will be lifted away by the operator.

In case the male plunger slides out and up the through the stripper plate without lifting up this plate, then the article can be forced out by the lower hydraulic operated shaft, or as stated this shaft can be raised simultaneously with the raising of the upper shaft 5.

In any case the complete stripping of the article away from the mold parts and the lifting of it to a point of easy grasp by the operator is provided for.

When the male die and stripper plate are raised clear of the female mold, and the movable section of the base of this female part is lowered to its original position, a new filling of material is inserted into

the female part, and the action of the shaft 5 is reversed.

As the shaft comes down carrying with it the male die and stripper plate, the plungers enter the mold and the plunger head strikes the stripper plate which is centered by hand, if necessary, so that it enters the female die, being carried along with the head of the male die.

The press may then be released, without attempting to exert great pressure, and the die parts as set together moved along a horizontal path from the press.

The press may also be used for imparting the full pressure desired, and a succession of molds brought in under the press, and thence passed around through a conveying, heating, or cooling system, so as to give the materials formed in the dies sufficient time to set.

I wish it understood that the features of my press involving the usual structures required for any die press, are described and illustrated merely to show any desired form of press, and not as limitations of the claim that follows. Also the particular method of engaging and disengaging the die parts may be varied to suit conditions, without departing from my invention.

Having thus described my invention, what I claim as new and desire to secure by Letters Patent, is:—

In a device of the character described, the combination of a male die part, a female die part, and a press, having a bed, and a reciprocating plunger shaft, of means for removably mounting and retaining the female and the male die parts on the press bed, and the shaft respectively, said mounting means being adapted to release both die parts while in engagement with each other, for the purpose described.

ROBERT HOLZ.
